(57) **ABSTRACT**

A component, such as a blade, vane or combustor wall of a gas turbine engine comprises two walls defining a coolant passage and has an array of pedestals extending between the two walls for heat removal. Each pedestal changes in cross-section along its length. Alternate rows of pedestals are arranged such that their larger cross-sectional area is adjacent one wall then the other. When a coolant flows through the passage it is forced to flow between one wall and the other wall so as to increase turbulence and hence mixing for a more even coolant temperature. The array of pedestals can also be used to tailor the individual heat loads on each wall independently and has the ability to use differing levels of blockage to counter adverse pressure gradients along successive rows of pedestals.

COOLING ARRANGEMENT FOR A COMPONENT OF A GAS TURBINE ENGINE

This invention relates to cooling arrangements for walls of heated components particularly but not exclusively in aerofoils, such as blades and vanes, and combustor walls used in gas turbine engines.

The performance of a gas turbine engine cycle, whether measured in terms of efficiency or specific output, is improved by increasing turbine gas temperatures. It is therefore desirable to operate the turbine at the highest possible temperature. For any engine cycle compression ratio or bypass ratio, increasing the turbine entry gas temperature, will always produce more specific thrust (e.g. engine thrust per unit of air mass flow). However as turbine entry gas temperatures increase, the life of an uncooled turbine component reduces, necessitating the development of more durable materials and/or the introduction of parasitic internal fluid cooling.

In modern engines, the high pressure (HP) turbine gas temperatures are now much hotter than the melting point of the blade materials used and therefore they require substantial quantities of cooling air. In some engine designs the intermediate pressure (IP) and low pressure (LP) turbines also require cooling.

Internal convection and external cooling films are the prime methods of cooling the aerofoils. HP turbine nozzle guide vanes (NGVs) consume the greatest amount of cooling air on high temperature engines. HP blades typically use about half of the NGV flow. The IP and LP stages downstream of the HP turbine use progressively less cooling air.

Turbine blades and vanes are cooled by using air from the HP or IP compressor that has by-passed the combustor and is therefore relatively cool compared to the main gas flow temperature. Typical cooling air temperatures are between 700 and 900 K and main working gas flow temperatures can be in excess of 2100 K. Extracting coolant flow therefore has an adverse effect on the engine operating efficiency. It is thus important to use this cooling air as effectively as possible.

Typically, cooled turbine components make optimum use of the coolant by maximising heat extraction, while minimising pressure drop needed to drive the coolant flow. Cooled components therefore employ intricate cooling passage networks and heat transfer augmentation devices, which can be cast into the walls of the components that are subject to particularly hot gases. These augmentation devices promote heat transfer by rendering the internal flow to be turbulent and by mixing the coolant in contact with the hot walls with the cooling flow.

One such augmentation device comprises an array of pedestals 34 cast on to internal walls 32, 33 of an aerofoil 30 as shown in FIG. 2. Conventionally, these pedestals are arranged either in an 'in-line' 34a or a 'staggered' 34b configuration (FIGS. 3 and 4 respectively) with respect to the direction of the cooling flow. Each pedestal 34 produces a pair of 'horse shoe' shaped vortices 36 in the flow immediately downstream of the pedestal. These vortices 36 promote heat transfer on the adjacent walls 32, 33. High levels of heat transfer are also produced on the leading edges 38 of the pedestals 30 and in the wake regions (36) where a local boundary layer becomes thinned. In these conventional arrangements 34a, 34b the heat transfer levels produced are similar on both adjacent internal surfaces 32i, 33i. This can be a limitation when one surface requires greater heat transfer than the other in order to achieve a constant temperature of the aerofoil 30. Uneven (wall material) temperatures give rise to undesirable thermal gradients that can cause excessive thermal stresses in the aerofoil or

other component, which can subsequently lead to premature component failure through low cycle thermal fatigue. In general, although a reasonable degree of mixing occurs as the flow moves downstream through the pedestal array, the fluid on inner surface 32i of wall 32 is not significantly mixed with the fluid on inner surface 33i of wall 33. Thus there can be a significant difference in temperatures of the two opposing walls 32, 33 causing low cycle thermal fatigue.

The object of the present invention is therefore to maintain a more constant temperature between opposing end walls of a heated component within a gas turbine engine, reducing the thermal gradient and increase the life of the aerofoil or other engine components.

According to the invention, there is provided a component for a gas turbine engine (10) comprising two walls defining a coolant passage and an array of pedestals extending between the two walls characterised in that at least one pedestal changes in cross-section between one wall and the other wall.

In one embodiment, the pedestal(s) tapers.

Preferably, the pedestal(s) comprises a first part having a first cross-sectional area and a second part having a second cross sectional area.

Preferably, the first cross-sectional area is greater than the second cross sectional area.

Preferably, the first part and the second part are concentric.

Alternatively, the first part and the second part are aligned at a common leading edge.

Alternatively, the first part and the second part are aligned at a common trailing edge.

Normally, in a first row of pedestals at least two of the pedestals have their greater cross sectional area adjacent the first wall.

Alternatively, in a second row of pedestals at least two of the pedestals have their greater cross sectional area adjacent the second wall.

Preferably, an array of pedestals comprises alternating first and second rows of pedestals.

Alternatively, in a first row of pedestals at least two of the pedestals alternate between having their greater cross sectional area adjacent the first wall and their smaller cross sectional area adjacent the first wall. In a second row of pedestals at least two of the pedestals alternate between having their greater cross sectional area adjacent the second wall and their smaller cross sectional area adjacent the second wall.

Preferably, the first and second rows are offset from one another so that in the downstream direction of the coolant the greater cross sectional area alternates between adjacent the first wall and the second wall.

Alternatively, the pedestals in the first row are in-line with the second row of pedestals with respect to the direction of coolant flow.

Alternatively, the pedestals in the first row are staggered with respect to the second row of pedestals with respect to the direction of coolant flow.

In another aspect of the present invention, the wall defines a hole for the passage of coolant therethrough and at least one adjacent pedestal is arranged such that its smaller cross-sectional area part is adjacent the hole.

Preferably, the smaller cross-sectional area part is positioned away from the hole, offset from the larger cross-sectional area part.

Preferably, the two parts of each pedestal are selected from the group comprising the cross-sectional shapes of circular, triangular, rectangular, diamond, parallelepiped, and ellipse.

Preferably, the two parts have the same cross-sectional shape.

Alternatively, the two parts have different cross-sectional shapes.

Alternatively, a second axis of one part is not aligned with a second axis of the other part.

Preferably, the component is a blade or vane of a turbine or a compressor of a gas turbine engine.

Alternatively, the component is a wall of a combustor of a gas turbine engine.

Embodiments of the invention will now be described by way of example only, with reference to the accompanying diagrammatic drawings, in which:—

FIG. 1 is a sectional side view of a gas turbine engine.

FIG. 2 is a section through a prior art turbine blade;

FIG. 3 is a view on section A-A in FIG. 2 showing a first prior art array of pedestals;

FIG. 4 is another view on section A-A in FIG. 2 showing a second prior art array of pedestals;

FIG. 5 is a view on section A-A in FIG. 2 (and C-C in FIG. 6) showing a first embodiment of an array of pedestals in accordance with the present invention;

FIG. 6 is a view on section B-B in FIG. 5 showing the first embodiment of the present invention;

FIG. 7 is a view on section D-D in FIG. 5 showing the first embodiment of the present invention;

FIGS. 8a-8f are plan view views on alternative pedestal shapes in accordance with the present invention;

FIG. 9 is a view on section A-A (and E-E in FIG. 6) showing a second embodiment of an array of pedestals in accordance with the present invention;

FIG. 10 is a view on section D-D in FIG. 8 showing the second embodiment of the present invention;

FIG. 11 is a part section through a turbine blade in accordance with a third embodiment of the present invention.

With reference to FIG. 1, a gas turbine engine is generally indicated at 10 and comprises, in axial flow series, an air intake 11, a propulsive fan 12, an IP compressor 13, an HP compressor 14, combustion equipment 15, a HP turbine 16, an IP turbine 17, an LP turbine 18 and an exhaust nozzle 19.

The gas turbine engine 10 works in the conventional manner so that air entering the intake 11 is accelerated by the fan to produce two air flows: a first air flow into the IP compressor 13 and a second air flow which provides propulsive thrust. The IP compressor 13 compresses the air flow directed into it before delivering that air to the HP compressor 14 where further compression takes place.

The compressed air exhausted from the HP compressor 14 is directed into the combustion equipment 15 where it is mixed with fuel and the mixture combusted. The resultant hot combustion products then expand through, and thereby drive, the HP, IP and LP turbines 16, 17 and 18 before being exhausted through the nozzle 19 to provide additional propulsive thrust. The HP, IP and LP turbines 16, 17 and 18 respectively drive the HP and IP compressors 14 and 13 and the fan 12 by suitable interconnecting shafts.

Referring now to FIGS. 5, 6 and 7, which show an array of pedestals 50 of a first embodiment of the present invention. The array of pedestals 50 is situated in a turbine blade 30 similar to the one shown in prior art FIG. 4. The turbine blade 30 is one of an annular array of radially extending blades of a stage of the HP turbine 16 and comprises a pressure side wall 32 and a suction side wall 33, joined together at the blades leading and trailing edges 35, 37 and via the pedestals 50.

The blade 30 and pedestals 50 are usually produced by the known lost wax casting process, which includes casting metal around a ceramic core in which the pedestals have been formed by pins introduced into the walls of a ceramic core die. Normally, the core die opens and closes along a central split

line with half of each pedestal produced in one half of the die and the other half produced in the other half. The two halves of the core die thus produce the part-pedestals 50a, 50b in the two adjoining wall halves 32 and 33 respectively. During the casting process the metal fuses to produce one complete or integral pedestal 50.

Pedestals 34 in conventional blade halves have the same geometric shape, diameter and co-axial centre-line location. For the present invention the blade or component is manufactured in the same manner, but each wall 32, 33 halve comprises part-pedestals 50a, 50b having different diameters, as in this embodiment, or cross-sectional areas. For the present invention, the array of pedestals 50 may be in any conventional pattern such as in-line or staggered and usually with respect to the general direction of coolant flow.

Each pedestal 50 of the present invention comprises a variation in cross-sectional area between the walls 32, 33. In the first embodiment the pedestals 50 comprise two parts of different diameters 50a, 50b and which are arranged substantially coaxial. However, the centres of the pedestal parts 51a, 51b do not necessarily need to be coaxial and for example either their leading edges 62 or trailing edges 64 may be aligned. The pedestals in rows 55r and 57r (row 55r is shown in FIG. 6) comprise a larger cross-sectional area part 50a adjacent the wall 32 and the smaller cross-sectional area part 50b adjacent the wall 33. These pedestals, which reduce in cross-sectional area from wall 32 are designated 52. In row 56r the pedestals 50 comprise the larger cross-sectional area part 50a adjacent the wall 33 and the smaller cross-sectional area part 50b adjacent the wall 32. These pedestals, which reduce in cross-sectional area from wall 32 are designated 53. The complete array of pedestals 50 in a blade or other component has further alternating rows of pedestals 55r, 56r, 57r arranged sequentially and generally in direction of the coolant flow therethrough.

This and the other arrangements of pedestals 50, 51 described herein change the shape of the coolant flow passage 49 between the walls 32, 33 and as the cooling fluid A passes along the passage 49 it is forced to flow from one wall to the other as it passes through each row of pedestals. Thereby mixing of the coolant is improved and provides a more even overall heat flux and attains a more desirable thermal profile throughout the component and its walls. Essentially, the arrangement of pedestals 50 forces the coolant to flow in a three dimensional regime rather than for the known pedestal arrays in two dimensions. As seen in FIGS. 5, 6 and 7 the coolant flow A is made to not only to zig-zag around the pedestals but also to zig-zag between the surface 32i and the surface 33i as the flow passes in a general downstream direction. This new cooling gas flow path promotes higher levels of turbulence and therefore improved mixing as heat transfers into the coolant near each wall. Thus the relatively hotter air flowing over the hotter pressure side wall 32 is mixed with the relatively cooler air flowing over the cooler wall 33, which does not require so much heat removal. Thus the thermal gradient within each wall 32, 33 and between pressure wall 32 and suction wall 33 is minimised and the life of the blade or other component increased.

It should be appreciated by the skilled artisan that the pedestals may be spaced and pitched differently to that shown. For example within each row 55r, 56r, 57r the pedestals may be spaced and pitched to preferentially cool certain parts of the component or placed around other features of the component. In addition or alternatively, the cross-sectional areas of the pedestals may be different depending on the desired cooling regime and component configuration. More pedestals may be positioned where for additional cooling is

required. The ratio of cross-sectional areas between the parts **50a**, **50b** of each pedestal may be varied again for preferential cooling of one wall to the other, or to force greater cross-wall turbulence. Variable pitching of the pedestals or rows of pedestals **50** can also be used to promote different levels of 'blockage' and turbulence and therefore improve heat removal and mixing within the coolant flow. This technique can be used as a tool to prevent internal flow migration in the presence of an adverse pressure gradient at either the coolant's entry or exit of the pedestal arrays. With respect to these modifications, the teachings of the pedestal arrangements in the Applicant's co-pending applications GB0601412.0, GB0601413.8, GB0601418.7 and GB0601438.5 are incorporated herein without departing from the scope of the present invention.

In a further modification of this first embodiment, pedestals **50** in each row **55**, **56**, **57** alternate between a pedestal with the larger cross-sectional area part **50a** adjacent the wall **32** and the next pedestal having the larger cross-sectional area part **50a** adjacent the wall **33** and so on. The sequentially adjacent rows **56** are offset from one another such that the larger cross-sectional area part **50a** in one row is downstream of the smaller cross-sectional part **50b** in an upstream row **55**. This modification may also be extended where pairs, triple or other multiples of adjacent pedestals within each row are arranged to alternate between the larger cross-sectional area part **50a** adjacent the wall **32** and the next multiple of pedestals having the larger cross-sectional area part **50a** adjacent the wall **33** and so on.

Furthermore, each half pedestal **50a,b**, **51a,b** may be of a different shape and chosen from the group comprising an ellipse, square, triangular, diamond or any other polygon some of which are shown in FIGS. **8a-d**. Polygonal shapes having edges or corners induce stronger and/or more vortices and can enhance mixing, however, they also induce a greater pressure loss to the coolant flow. The use of polygonal shapes may therefore be used locally around hot spots in on the walls **32**, **33**, **21**. The two parts (**50a**, **51a**, **53a**, **50b**, **51b**, **53b**) of the pedestal may have different cross-sectional shapes.

In FIG. **8d**, an alternative pedestal **55** comprises a tapering shape between wall **32** and wall **33**. This shape may be preferable where the whole pedestal is formed on one half of the mould and is therefore a preferred shape having no re-entrant or step features. Alternate tapering pedestals **55** extend from either wall **32** or **33**.

In FIG. **8e**, another alternative pedestal **58** comprises a tapering part **58b** extending from wall **33** and a cylindrical part **58a** extending from wall **32**. The two parts define a gap **58c** therebetween, which is angled downwards to direct coolant downwardly and create further beneficial turbulence to improve mixing between the walls. Of course the parts **58a** and **58b** may be any cross-sectional shape.

Referring to FIGS. **9** and **10**, a pedestal **59** in an array of pedestals comprises two elongate parts **59a**, **59b**, each part in this example being elliptical in cross-sectional shape and having a first and a second axes **60**, **61**. The first axis **60** is along the larger dimension of the part e.g. **59b**. The pedestal **59** is arranged such that the first axis **60** of one part **59a** is normal to the first axis **60** of the other part **59b**. As shown in the figures, the row **56r** has the first axis **60** of part **59a**, adjacent wall **32**, normal to the coolant flow direction A and the first axis **60** of part **59b**, adjacent wall **33**, parallel to the coolant flow direction A. Rows **55r** and **57r** have pedestals orientated at 90 degrees to those in row **56r**. Although the overall cross-sectional areas of the parts **59a**, **59b** are similar to one another, due to their orientation and shape the coolant flow areas adjacent the two walls **32**, **33** (i.e. between parts

59b of adjacent pedestals **59**) change from row to row and thereby force the coolant to flow from one wall to the other and vice versa as described hereinbefore.

Referring to FIG. **11**, the present invention may also be utilised to accommodate cooling holes **70** defined through the wall **32**. The pedestal **50** upstream of the cooling hole **70** has both parts with their leading edges **62** aligned and the downstream pedestal has both parts with their trailing edges **64** aligned, then the space between the half pedestals **50b** will be larger than otherwise. This enlarged gap when arranged on the pressure side wall **32** of aerofoils **30** is used to accommodate a row of film cooling holes **70**, without the need to drill or laser through any pedestals **50**. Not only does this arrangement simplify any hole drilling process, but also preventing loss of pedestals means that local thermal hot spots do not occur where pedestals have been destroyed.

An advantage of having at least one adjacent pedestal arranged such that its smaller cross-sectional area part **50b** is adjacent the hole **49** is that greater space is provided to accommodate an array of cooling holes **42**, only one cooling hole **42** being shown. In conventional aerofoils the cooling hole **42** position would result in the absence of the entire pedestal **50**. A further advantage is that the cooling gas flow around the smaller part-pedestal **50b** is less turbulent so that the gas may better enter the cooling hole **42** and improve the cooling film on an external surface **44** of the aerofoil **30**. Thus although less heat will be removed by the smaller diameter part-pedestal **50b**, the improvement to the cooling film overall improves the cooling of the component **30**.

Referring back to FIG. **1**, the combustor **15** is constituted by an annular combustion chamber **20** having radially inner and outer double wall structures **21** and **22** respectively. Similarly to the turbine blade **30**, each of the combustor's double walls **21**, **22** have two walls **32**, **33** and an array of pedestals **50** disposed therebetween. The array of pedestals **50** is in accordance with any of the embodiments of the present invention described above.

It should be appreciated by the skilled artisan that any number of the pedestal shapes described herein may be combined and geometries that would become possible is almost endless and too numerous to describe here. However, the principle benefits of the pedestal arrangements are: increased levels of heat transfer from the walls, improved mixing and therefore a more even coolant temperature, the ability to tailor the individual heat loads on each wall independently and the ability to use differing levels of blockage to counter adverse pressure gradients along successive rows of pedestals.

Also it should be appreciated by the skilled addressee that each pedestal **50** may be formed completely on one wall **32**, **33** or that the length of each part-pedestal **50a**, **50b** may vary and not be an exact half the full length of the pedestal.

I claim:

1. A component for a gas turbine engine comprising a first wall and a second wall defining a coolant passage and an array of pedestals extending between the first wall and the second wall wherein at least one pedestal changes in cross-section between the first wall and the second wall, the pedestal(s) includes a first part having a first cross-sectional area and a second part having a second cross sectional area, and the first part and the second part are aligned at a common trailing edge.

2. A component as claimed in claim 1 wherein the pedestal (s) tapers.

3. A component as claimed in claim 1 wherein the first cross-sectional area is greater than the second cross sectional area.

4. A component as claimed in claim 1 wherein in a first row of pedestals at least two of the pedestals have their greater cross sectional area adjacent the first wall.

5. A component as claimed in claim 4 wherein an array of pedestals comprises alternating first and second rows of pedestals.

6. A component as claimed in claim 4 wherein the pedestals in the first row are in-line with the second row of pedestals with respect to the direction of coolant flow.

7. A component as claimed in claim 4 wherein the pedestals in the first row are staggered with respect to the second row of pedestals with respect to the direction of coolant flow.

8. A component as claimed in claim 1 wherein in a second row of pedestals at least two of the pedestals have their greater cross sectional area adjacent the second wall.

9. A component as claimed in claim 1 wherein the wall defines a hole for the passage of coolant therethrough and at least one adjacent pedestal is arranged such that its smaller cross-sectional area part is adjacent the hole.

10. A component as claimed in claim 1 wherein the two parts of each pedestal are selected from the group comprising the cross-sectional shapes of circular, triangular, rectangular, diamond, parallelepiped and ellipse.

11. A component as claimed in claim 10 wherein the two parts have the same cross-sectional shape.

12. A component as claimed in claim 11 wherein a second axis of one part is not aligned with a second axis of the other part.

13. A component as claimed in claim 1 wherein the component is a blade or vane of a turbine or a compressor of a gas turbine engine.

14. A component as claimed in claim 1 wherein the component is a wall of a combustor of a gas turbine engine.

15. A component for a gas turbine engine comprising a first wall and a second wall defining a coolant passage and an array of pedestals extending between the first wall and the second wall wherein at least one pedestal changes in cross-section between the first wall and the second wall, and in a first row of pedestals at least two of the pedestals alternate between having their greater cross sectional area adjacent the first wall and their smaller cross sectional area adjacent the first wall.

16. A component as claimed in claim 15 wherein in a second row of pedestals at least two of the pedestals alternate between having their greater cross sectional area adjacent the second wall and their smaller cross sectional area adjacent the second wall.

17. A component as claimed in claim 15 wherein the first and second rows are offset from one another so that in the downstream direction of the coolant the greater cross sectional area alternates between adjacent the first wall and the second wall.

18. A component for a gas turbine engine comprising a first wall and a second wall defining a coolant passage and an array of pedestals extending between the first wall and the second wall wherein at least one pedestal changes in cross-section between the first wall and the second wall, two parts of each pedestal are selected from the group comprising the cross-sectional shapes of circular, triangular, rectangular, diamond, parallelepiped and ellipse, and the two parts have different cross-sectional shapes.

19. A component as claimed in claim 18 wherein the first part and the second part are concentric.

20. A component as claimed in claim 18 wherein the first part and the second part are aligned at a common leading edge.
